UNITED STATES PATENT OFFICE.

HARRY ALBERT GRIFFITHS, OF BIRMINGHAM, AND RICHARD HANSON GRIFFITHS,
OF SUTTON COLDFIELD, ENGLAND.

PRESS FOR OPERATING ON METAL SHEETS OR FOR LIKE PURPOSES.

Application filed October 17, 1925, Serial No. 63,066, and in Great Britain November 19, 1924.

This invention relates to presses for operating on metal sheets and for like purposes. Ordinarily it is necessary to provide in the main frame of such machines a deep gap or throat between the upper and lower tools to accommodate the sheets on which the tools operate. The gap extends from the rear of the tools in the plane of the sheet. To counteract the springiness which would otherwise be present in the main frame, due to the size of the gap, it is usually necessary to make the main frame very massive. Machines as ordinarily constructed are therefore cumbersome, unduly heavy, and correspondingly costly.

The object of the present invention is to avoid the ordinary liability to springiness in the frame in a manner which affords all the required accommodation for the sheet to be passed between the tools, and at the same time enables the dimensions and mass of the frame to be greatly reduced.

The invention comprises the provision in the frame, of a gap which extends downwardly from the region of the tools (preferably at right angles to plane of the un-worked sheet), and means for deflecting into the gap the worked portion of the sheet which has passed between the tools.

The invention also comprises the provision at the upper end of the gap, of a chute for receiving portions cut from the sheet by the tools and delivering them to the rear or other part of the machine.

In the three accompanying sheets of explanatory drawings:—

Figure 1 is a side elevation of a press constructed in accordance with this invention.

Figure 2 is a front elevation of the machine, and Figure 3 a sectional plan on 1, 2, Figure 2.

In the construction of a press as illustrated, for cutting out from thin metal sheets such blanks as are required in the manufacture of circular metal boxes, the tools are preferably arranged with their axis inclined to the vertical, so that the normal plane of the sheet *a* to be acted on is inclined downwardly to the horizontal. Immediately behind the part carrying the lower or fixed tools *b* the main frame is formed with a deep gap *c* which extends below the working position of the sheet in a direction at right angles to the plane of the sheet.

The main frame consists of a casting comprising principally two upright cheeks *d* which are joined and stiffened by suitable transverse portions as well as by the portions which carry the upper and lower tools. Between or on the outer sides of the cheeks at a position behind the lower tools a deflector *e* or deflectors *e* is or are arranged. The deflector presents a concave surface to the portion of the sheet which has passed the tools and serves to deflect the worked portion of the sheet into the gap. Also behind the tools and on the main frame, a chute *f* is arranged to receive the blanks ejected from the machine and to convey them to any required position behind the machine. Preferably the chute is pivotally mounted and is actuated by a lever *g*, link *h*, and lever *i* from a cam *j*, this mechanism serving to lower the chute into contact with the sheet and to raise it slightly clear of the sheet at appropriate intervals in each cycle of operations.

In combination with the upper tool *q* carried on the slide *k* is preferably arranged an ejecting lever *l* adapted to detach the work pieces which may adhere to the upper tool during its upward movement. This lever is connected by a link *m* to a lever *n* which is actuated by a cam *o*. The lever *l* acts on an ejecting plunger *s* located within the tool *q*.

Also the slide *k* is preferably fitted with a supplementary deflector *r* which during the latter part of each downward stroke of the slide presses the adjacent portion of the sheet into the gap *c*.

Behind the lower tool a renewable and preferably adjustable guiding edge piece *p* may be provided for guiding the deflected portion of the sheet.

By this invention we are able to provide the necessary stiffness in the frame in a manner which results in important reductions in the size and weight of the frame, and in addition to corresponding savings in cost we are able to secure advantages as regards both design and convenience in use.

Having thus described our invention what we claim as new and desire to secure by Letters Patent is:—

1. In a press for operating on metal sheets and the like, in combination, a reciprocating tool, a frame provided with a gap, said gap being angularly disposed with respect to the

working plane of said tool, and means secured to said tool for bending the worked portion of the sheet which has passed said tool and deflecting the sheet into said gap.

5 2. In a press as claimed in claim 1, an auxiliary deflector secured to said frame at the angle of the gap and the working plane of the tool.

3. In a press as claimed in claim 1, a chute

pivoted to said frame, and means operable upon movement of the tool away from the sheet for moving said chute into contact with said sheet to scrape formed articles from the sheet.

In testimony whereof we have signed our names to this specification.

H. A. GRIFFITHS.
